UNITED STATES PATENT OFFICE

CLAYTON M. MORRIS, OF LOS ANGELES, CALIFORNIA

IRONING BOARD CONSTRUCTION

Application filed January 15, 1930. Serial No. 420,893.

This invention relates to a separable ironing board particularly adapted for being used to support a variety of different shaped garments during ironing and pressing.

- 5 An object of the invention is to provide improved means for removably and interchangably supporting any one of a plurality of ironing boards in a convenient position for use.
- 10 Another object of the invention is to stabilize and strengthen the means for mounting the removable section of the ironing board upon the base portion thereof.

15 Other objects and advantages, such as simplification of structure, convenience in use and lessened cost of manufacture, may hereinafter appear.

20 Referring to the accompanying drawings which illustrate what is at present deemed to be a preferred embodiment of the invention.

Fig. 1 is a plan view of the complete device.

Fig. 2 is a side elevation thereof.

25 Fig. 3 is an end elevation looking from left to right of Figs. 1 and 2.

Fig. 4 is a plan view of one of the ironing boards proper showing the same removed from the base section.

30 Referring in detail to the drawings, to the flat base 5 is secured, by any suitable means (not shown), a supporting block or standard 6. The upper portion of said standard 6 is provided on each side with a horizontal bead or rib 7 which is spaced slightly below the upper edge of said standard 6.

35 With the standard 6 cooperates a plurality of removable ironing boards, one of these, designated 8, being shown in Figs. 1, 2 and 3 attached to the standard in position for use.

40 The means for detachably securing ironing board 8 in place comprises, in the illustrated embodiment of the invention, a pair of parallel, cooperating cleats 9 secured to the under side of the ironing board 8 near one end thereof in spaced relation to each other. Each of these cleats is provided along its inner face, preferably at about its mid-width, with a groove 10 which is adapt-

ed to telescope over the rib 7 of the standard 6.

45 The relative position of the ironing board 8, standard 6 and base 5 are such as are commonly employed in devices of this kind, the invention residing in the means for removably securing the ironing board proper to the remaining portion of the device. This securing means comprises not only the tongue or groove connection already described, but also a device for yieldingly holding the parts together when assembled as shown in Figs. 1, 2 and 3 of the drawing.

50 The means for holding the parts yielding together as just stated, comprises a two-part catch device, one part 12 of which is secured to the end portion of the upper part of standard 6 and the other part 14 of which is secured to the under side of the ironing board proper.

55 As shown in the drawings, part 12 consists of a pin or stud which projects from the standard 6 and which is provided at each side with a concavity or recess 15, and the part 14 consists of a clip 16 having at each side a spring flange 17 provided with a terminal lip 18 which springs into the recesses 15 of the stud 12 thereby to hold the parts to which they are attached yieldingly together.

60 The stud 12 is provided with a pointed end portion 20 which is adapted to be forced between the lips 18 when the ironing board proper is put in place.

65 In Fig. 4 is shown an ironing board proper 25 of different shape from the ironing board already described. Said ironing board 25 is of the "duck-bill" shape, being provided with an expanded portion 26 which is adapted for being used to support a wider garment than could be properly supported by the ironing board 8 which has already been described.

70 The tongue and groove construction formed on parts 6, 7 and 9 is such, and the groove 10 is so positioned that when the ironing board proper is mounted upon the standard 6 the entire weight thereof, together with any pressure which may be imposed upon it, is received by the upper edge of the standard 6 and therefore does not tend to break the grooved portions of the cleats 9.

90

95

100

105

The standard 6 is shown attached to the base 5 by means of screws 30, and the cleats 9 are shown attached to the ironing board proper 8 by means of screws 31.

5 It is to be understood that the two-part catch consisting of the elements 12 and 14 may be reversely arranged if desired, the essence of the invention not depending upon the relative positions of the male and female portions of said catch. The two parts of 10 the catch will resist pulling apart under any strain to which the device will be apt to be subjected during use, but will permit the ironing board proper to be readily attached and detached.

15 When the device is constructed according to the design shown in the drawings the main parts thereof may be constructed of wood, but it is to be understood that metal may be substituted for wood, and various other changes 20 within the scope of the appended claims may be made in the construction without departing from the spirit of the invention.

25 When the device is made of wood the base 5, standard 6 and ironing boards proper 8 and 25 may each be boards cut into the desired shape by the use of saws adapted for the purpose.

30 It will be seen that this invention provides an ironing board proper which has a flat unmodified lower face to which the catch and mounting means may be secured in a simple inexpensive manner.

Claims:

35 1. A separable ironing board construction comprising a base board, a board secured in an upright position to said base board to form a standard, there being a substantially horizontal rib projecting from each side of the 40 upper portion of said standard, an ironing board proper having cooperating parallel spaced cleats secured to one face thereof, said cleats having grooves adapted to telescope over said ribs, and a catch device comprising two parts which are yieldingly engageable 45 with each other to releasably hold said ironing board proper in its attached position upon said standard, one part of said catch being attached to said ironing board proper and the other part thereof being attached to 50 said standard, one part of said catch being a metallic plate having two cooperating spring arms integral therewith, and the other part of said catch comprising a part positioned 55 to be embraced by said arms.

60 2. A separable ironing board construction comprising a base, a standard carried by said base, an ironing board proper having on its lower face means to mount said board detachably upon said standard in a longitudinally 65 slideable manner, and a two-part catch one part of which is secured to one end of said standard and the other part of which is secured to the lower face of the ironing board proper, one part of said catch comprising a

metallic plate having integral therewith a pair of cooperating spring arms, and the other part of said catch comprising a part positioned to cooperate with said arms.

70 In testimony whereof I hereunto affix my signature.

CLAYTON M. MORRIS.
